(57) **CLAIM**

The ornamental design for an elastomeric stopper for containers of pharmaceutical preparations, as shown and described.

DESCRIPTION

FIG. 1 is a front elevational view of the elastomeric stopper for containers of pharmaceutical preparations showing my new design.

FIG. 2 is a left side elevational view thereof.

FIG. 3 is a top plan view thereof.

FIG. 4 is a bottom plan view thereof.

FIG. 5 is a sectional view taken in the direction of the arrows on line 5-5 of FIG. 3.

FIG. 6 is a perspective view of thereof; and,

FIG. 7 is another perspective view of thereof.
